UNITED STATES PATENT OFFICE

166,915

COLLAR OR THE LIKE

Mary Jane Iwaniec, Bartow, Fla.

Application January 23, 1952, Serial No. 18,180

Term of patent 7 years

(Cl. D3--8)

To all whom it may concern:

Be it known that I, Mary Jane Iwaniec, a citizen of the United States, residing at Bartow, county of Polk, State of Florida, have invented a new, original, and ornamental Design for a Collar or the like, of which the following is a specification, reference being had to the accompanying drawing, forming a part thereof.

In the drawing:

Fig. 1 is a front view of a collar or the like showing my new design; and

Fig. 2 is a rear view thereof.

I claim:

The ornamental design for a collar or the like, substantially as shown.

MARY JANE IWANIEC.
